DOUGLAS TURNER, OF ST. LOUIS, MISSOURI, ASSIGNOR TO THE MEASUREGRAPH COMPANY, OF ST. LOUIS, MISSOURI, A CORPORATION OF MISSOURI.

FABRIC-MEASURING AND COST-COMPUTING MACHINE.

1,386,386.

Specification of Letters Patent.

Patented Aug. 2, 1921.

Application filed February 19, 1920. Serial No. 359,855.

To all whom it may concern:

Be it known that I, DOUGLAS TURNER, a citizen of the United States, residing in the city of St. Louis and State of Missouri, have 5 invented new and useful Improvements in Fabric-Measuring and Cost-Computing Machines, of which the following is a specification.

This invention relates to a fabric measuring and cost-computing machine. The type 10 of machine to which the invention is especially applicable, is used in selling goods at retail, and comprises in its construction a housing or casing through which a gap or 15 throat is formed. The fabric, in being measured is pulled through this gap, and rotates a measuring roller, the rotation of which is imparted to indicating mechanism which is exposed to view at the upper side of the 20 casing or housing. These machines are also provided with a knife or cutter, which notches the edge of the fabric measured off, to indicate the point where the piece must be cut off from the roll or bolt. As heretofore constructed, this knife has been mounted about in alinement with the point where the fabric emerges from the gap, and the 25 computations of the indicating mechanism are made with reference to the plane of movement of the knife as the zero point; in other words, the forward edge of the fabric before it is measured, should be lined up 30 with the plane of the knife. This method of alining the fabric to be measured gives 35 an accurate result if the operator is careful to see to it that the forward edge of the fabric is properly alined, but there is a tendency on the part of some operators to take hold of the edge of the fabric in such 40 a way, as it emerges from the gap, that the measurement is begun with a considerable amount of the fabric already beyond the 45 alining point. When this occurs, there is a loss of goods by the retailer, because this projecting portion of the fabric is not measured, and therefore, not paid for by the purchaser.

The general object of the present invention is to provide a machine having a construction which will overcome this difficulty and prevent this loss to the retailer. In accomplishing this I provide an alining point on the machine, a considerable distance be-

yond the point where the cloth emerges from the gap, and provide means for indicating 55 this alining point in a simple manner. The amount of fabric lying beyond the emerging point from the gap, is sufficient to enable the operator to get a good grasp on the fabric in pulling it through the machine, 60 and there is therefore, no temptation to pull the forward edge of the fabric farther than necessary past the alining point, before the measuring begins. The invention concerns 65 itself especially with the novel features of construction of such a machine which co-operate to accomplish the result referred to above.

Further objects of the invention will appear hereinafter.

The invention consists in the novel features, and in the general combination of parts to be particularly described herein-after, all of which contribute to produce a simple and efficient fabric measuring and 75 cost-computing machine. A preferred embodiment of my machine will be particularly described in the following specification, while the broad scope of my invention will be pointed out in the appended claims. 80

In the drawing,

Figure 1 is a plan of the machine embodying my invention, and illustrating the manner in which the fabric is pulled through the machine in making a measure- 85

Fig. 2 is a front elevation of the machine shown in Fig. 1;

Fig. 3 is a horizontal cross-section through the machine, partially broken away, and 90 taken about on the line 3—3 of Fig. 4;

Fig. 4 is a vertical section through the machine taken about on the line 4—4 of Fig. 3;

Fig. 5 is a vertical section through the 95 machine taken about on the line 5—5 of Fig. 3;

Fig. 6 is a vertical section taken about in the plane of the section 4—4, of Fig. 3 but showing the parts in another position; and 100

Fig. 7 is a fragmentary view further illustrating the general construction of the machine, certain parts being broken away.

The machine includes a casing or housing 1, the body 2 of which is of rectangular or 105 box form, the other end 3 of the housing be-

ing of substantially cylindrical form. The upper face of the machine is provided with an indicating dial 4 for indicating the length of the fabric measured off, and has 5 two windows through which the charts 5 are visible; these charts or webs carry the computations or figures and coöperate with fixed scales 6, to indicate the charge to be made for the amount of goods indicated at the 10 dial 4.

The fabric 7 is pulled through the machine in the direction of the arrow (see Fig. 1), that is to say, the fabric is pulled through a gap 8 formed in a horizontal 15 plane through the housing of the machine (see Fig. 2). The fabric emerges from this gap in the plane of the line 9, (see Fig. 1).

Heretofore, the line 9, or a point near it, has been used as the alining point at which 20 the edge of the fabric is cut. According to my invention, I provide for alining the fabric on a line or plane beyond this line 9, with respect to the direction of pull of the fabric in being measured. In this way, 25 there is no objection to the presence of a small quantity of the fabric projecting from the gap and beyond the plane of the line 9.

In order to accomplish this, I prefer to provide the housing 1 with a laterally projecting portion 10 (see Fig. 1) which operates as a special housing or knife-pocket for a knife 11 which is movably mounted within it. The gap 8 cuts through the side of the knife-pocket 10 (see Fig. 2), so that the 30 edge of the fabric may lie in the path of the edge of the knife 11 as it descends. It should be explained, in connection with Fig. 1, that the edge 12 of the fabric 7 will eventually lie near the inner end of the 35 gap 8 (see Fig. 2). The fabric is shown in this position to avoid covering parts of the mechanism.

The knife 11 may be mounted in any suitable manner, for example, upon a pivot-shaft 14, the rear end of the knife having a 40 coil spring 15 attached to it, which normally holds the knife in an elevated position (see Fig. 2); as the knife descends, the blade 16 which it carries coöperates with a 45 fixed blade 17 which may be attached to the inner face of the outer wall 18 of the knife-pocket 10.

As the fabric 7 is pulled through the gap 8, it rotates a measuring roller 19 (see Fig. 4) which is mounted in the housing below the gap, and when this measuring roller rotates, its shaft 20 (see Fig. 7) rotates a pinion 21 which drives a gear-train 22 including a gear wheel 23 (see Figs. 3 and 5); 50 this gear wheel 23 lies between two gear wheels 24, and meshes with them, so as to rotate two drums or take-up rollers 25 and 26 (see Fig. 3), upon which charts 27 Fig. 1 wind; these charts carry the computations 55 or numbers referred to above.

Through suitable driving-mechanism 28, (see Fig. 4) the indicating hands 29 and 30 on the dial 4 are actuated.

In order to hold the fabric against the measuring roller 19, I provide a presser-roller 31 (see Fig. 6), which is mounted to rotate freely between two arms 32 Fig. 3 which extend laterally from a movable frame or rock-shaft 33. This rock-shaft has two substantially horizontal arms 34, to 75 which springs 35 attach (see Fig. 4) and these springs tend to pull the presser-roller 31 down against the measuring roller 19. This construction is substantially the same as in Fig. 15 of Patent No. 1,336,230 to 80 W. E. Hosch, deceased, dated April 6, 1920.

I provide latching means for normally latching the presser-roller away from the measuring roller. For this purpose, the rock-shaft 33 is provided with another laterally projecting arm 36 (see Figs. 3 and 6). Coöperating with this arm 36, I provide a latch or detent 37, and I provide means substantially in line with the knife for actuating this latching means to release the arm 90 36, and thereby permit the presser-roller to descend onto the measuring roller. The latch 37, may be in the form of a bolt, the outer end of which is guided to slide through a vertical frame plate 38. I provide a controlling member for this latch, and this controlling member is preferably guided to move at right angles to the length of the fabric, or parallel with the presser-roller. For this purpose, beyond the frame 95 plate, the latch 37 is pivotally attached to a lever 39, and the lower end of this lever is attached to the inner end of a stem 40, the outer end of which carries a controlling member in the form of a starting button 41; this stem is guided to slide through the wall of the knife-pocket, and through an opening in a guide-bracket 42. A spring 43 attached to the guide-bracket 42 and to the stem 40 returns this starting button to its 100 normal position after it has been operated.

I provide means for indicating a starting point for alining the end of the fabric. This may be indicated by words or marks on the side of the starting button. 115

I provide automatic means actuated by the depression of the knife 11 for withdrawing the presser-roller from the measuring roller, and this means operates by depressing the arm 36 sufficiently to enable the 120 latch 37 to snap over the upper edge of the arm and hold the same depressed. In order to accomplish this, I provide a lever 44 which is pivoted at 45 on the frame plate 38, and the outer end of this lever is actuated in any suitable way from the knife, for example, I may connect it by means of a link 46 with an arm 47 rigidly attached to the pivot or shaft 14 of the knife. 125

In order to enable the knife to be operated, 130

it is provided with a thumb-plate 48 which runs in an arcuate slot 49 in the outer wall 18 of the upper portion of the knife-pocket.

The mode of operation of the machine 5 will now be briefly described.

The fabric 7 which is to be measured, is pulled through the gap 8 in the direction of the arrow, so that its forward edge is about in alinement with the wall 18 of the knife-pocket 10. The starting button 41 is then pressed inward and this withdraws the detent or latch 37 from above arm 36 (see Fig. 6) so as to permit the spring 35 to pull the presser-roller down onto the measuring roller. 10

15 The fabric is then pulled through the machine. When the desired amount of fabric has been measured off, the knife 11 is then depressed so as to notch the edge of the fabric at the point where it is to be cut off from the roll or bolt. The depression of the knife 20 in this way operates through a link 46 (see Fig. 6) and lever 44 to force the arm 36 downwardly, thereby rocking the rock-shaft 33 so as to lift the presser-roller away from 25 the measuring roller; when the arm 36 is sufficiently depressed, the latch 37 snaps over its upper edge and in this way latches the presser-roller in its elevated or withdrawn position. In connection with the mode of 30 operation of the latch 37 and the arm 36, it should be understood, that when the presser-roller 31 is in contact with the measuring roller, the arm 36 will not lie above the latch; for this reason it is unnecessary to 35 bevel the upper face at the end of the latch 37; the end of the latch is simply held against the side face of the arm 36 by the spring 43 until the arm 36 is depressed, at which time the latch simply snaps over its 40 upper edge.

It is understood that the embodiment of the invention described herein is only one of the many embodiments my invention may take, and I do not wish to be limited in the 45 practice of my invention nor in my claims, to the particular embodiment set forth.

What I claim and desire to secure by Letters Patent is:

1. In a fabric measuring and cost-com- 50 puting machine, the combination of a housing having a laterally projecting portion forming a knife pocket, said housing having a gap formed therethrough, through which the fabric may pass in measuring the same, 55 a measuring roller mounted in said housing, indicating mechanism actuated thereby, a presser-roller to coöperate with the measuring roller, and to press the fabric against the same, means for forcing the presser-roller 60 toward the measuring roller, means for latching the presser-roller away from the measuring roller, a knife mounted at said knife-pocket for notching the edge of the fabric, and a controlling member lying ad- 65 jacent said knife pocket for actuating the

latching means to release the presser-roller.

2. In a fabric measuring and cost-computing machine, the combination of a housing having a laterally projecting portion 70 forming a knife-pocket, said housing having a gap passing through said knife-pocket, through which the fabric may pass in measuring the same, a measuring roller mounted in said housing, indicating mechanism actuated thereby when the fabric is pulled through said gap, a knife mounted in said knife-pocket for notching the edge of the fabric, and means for indicating an alining point for the fabric adjacent said knife-pocket. 75

3. In a fabric measuring and cost-computing machine, the combination of a housing having a laterally projecting portion forming a knife-pocket, said housing having a 85 gap passing through said knife-pocket, through which the fabric may pass in measuring the same, a measuring roller mounted in said housing, a presser-roller coöperating with the measuring roller, indicating mechanism actuated by the measuring roller when the fabric is pulled through the gap, a knife mounted in the knife-pocket for notching the edge of the fabric, a spring for pulling the presser-roller toward the measuring 90 roller, a latch for holding the presser-roller away from the measuring roller and a starting button substantially in alinement with the knife, and guided through said knife-pocket, and means actuated thereby for releasing the presser-roller from the latch. 100

4. In a fabric measuring and cost-computing machine, the combination of a measuring roller, a presser-roller coöperating therewith, a spring tending to pull the presser-roller against the measuring roller, means for latching the presser-roller away from the measuring roller, a controlling member having means thereupon to indicate 105 that the cloth to be measured should be alined with the same, and means actuated by the controlling member for releasing the presser-roller to permit the same to engage with the measuring roller. 110

5. In a fabric measuring and cost-computing machine, the combination of a measuring roller, a presser-roller coöperating therewith, a spring tending to pull the presser-roller against the measuring roller, a rock-shaft carrying the presser-roller and having an arm, a detent to engage said arm to hold the presser-roller away from the measuring roller, a controlling member located adjacent the alining point for the fabric and guided to move in a direction substantially parallel with the presser-roller, and a connection between said controlling member and said detent for moving the detent to release the presser-roller. 120

6. In a fabric measuring and cost-com- 130

puting machine, the combination of a measuring roller, a movable frame for supporting the presser-roller, a presser-roller carried thereby, a knife for notching the edge 5 of the goods and having a pivot, a lever for engaging the presser-roller frame to move the presser-roller away from the measuring roller, means for connecting said lever with said pivot to effect the raising of the presser- 10 roller when the knife is operated, a latch for engaging the movable frame to hold the same with the presser-roller removed from the measuring roller, and a starting button substantially in alinement with the knife 15 and having means connecting it with the latch for releasing the presser-roller frame from the latch.

7. In a fabric measuring and cost-computing machine, the combination of a housing 20 including a laterally projecting portion forming a knife-pocket, said housing having a gap formed therethrough, through which the fabric may pass in measuring the same, a measuring roller mounted in said housing, 25 a presser-roller coöperating therewith, having a spring for pulling the same toward the measuring roller, a rocking frame carrying the presser-roller and having a projecting arm, a knife in said knife-pocket for 30 notching the edge of the goods, a lever actuated thereby and engaging said arm to

move the rocking frame and the presser-roller away from the measuring roller, a spring-pressed latch for engaging said arm to latch the presser-roller away from the measuring roller, and a starting button having means to release the rocking frame from the latch when it is moved for starting. 35

8. In a fabric measuring and cost-computing machine, the combination of a housing 40 having a laterally projecting portion forming a knife-pocket, a fixed blade disposed adjacent to the outer wall of said knife-pocket, said housing having a gap through the same and through the knife pocket, a knife pivotally mounted in said knife pocket, a spring normally holding said knife in its raised position, a blade carried by the knife to co-operate with the first named blade, a measuring roller within said housing, indicating 45 mechanism actuated thereby, a presser-roller coöperating with the measuring roller, means for latching said presser-roller away from the measuring roller, and a starting button in substantial alinement with said 50 knife and connected with the latching means to release the presser-roller and permit the same to descend onto the measuring roller.

In testimony whereof I have hereunto set my hand.

DOUGLAS TURNER.
